UNITED STATES PATENT OFFICE.

WILLIAM F. HARTIG, OF EVANSVILLE, INDIANA.

DESIGN FOR A SHANK FOR CULTIVATOR-STANDARDS.

SPECIFICATION forming part of Design No. 34,869, dated July 30, 1901.

Application filed June 5, 1901. Serial No. 63,314. Term of patent 14 years.

To all whom it may concern:

Be it known that I, WILLIAM F. HARTIG, a citizen of the United States, residing at Evansville, in the county of Vanderburg and State of Indiana, have invented and produced a new and original Design for a Shank for Cultivator-Standards, of which the following is a specification.

The present invention relates to a new design for the shank of a cultivator-standard; and the object thereof is to provide a design of this character that is new, original, and useful.

The leading feature of the design resides in a shank consisting of a curved body having on its opposite sides a plurality of longitudinally-disposed spaced ribs, which are also curved, said body being furthermore provided at its rear edge with a longitudinally-disposed curved rib.

Minor and less important features reside in tapering the rearwardly-projecting rib from its upper toward its lower end and in providing a bolt-receiving opening through the lower end of the shank, said opening passing through from the front to the rear thereof.

In the drawings, Figure 1 is a view in elevation of one side of the standard. Fig. 2 is a similar view of the opposite side. Fig. 3 is a cross-section taken on the lines X X of Fig. 2, and Fig. 4 is a cross-section taken on the line Y Y of Fig. 2.

Similar numerals of reference designate corresponding parts in all the figures of the drawings.

The new design, as shown in the accompanying drawings, consists of a curved body 10, having on its opposite sides a plurality of longitudinally-disposed spaced ribs 11, which are also curved. The ribs are separated by wide deep furrows or valleys and are wider apart at their upper than at their lower ends. (See Figs. 3 and 4.) The body is furthermore provided along its rear or outer edge with a rearwardly-extending curved longitudinally-disposed rib 12, which rib, as shown, tapers from its upper toward its lower end and is arranged along the center of the rear or outer edge of the body. A bolt-receiving opening 13 passes through the lower end of the body, from the front to the rear thereof.

Having thus described the invention, what I claim as new, and desire to secure by Letters Patent, is—

The design for a shank for cultivator-stands as herein shown and described.

In testimony that I claim the foregoing as my own I have hereto affixed my signature in the presence of two witnesses.

WILLIAM F. HARTIG.
